UNITED STATES PATENT OFFICE.

JOSEPH F. JOY, OF PITTSBURGH, PENNSYLVANIA, ASSIGNOR TO JOY MACHINE COMPANY, OF PITTSBURGH, PENNSYLVANIA, A CORPORATION OF DELAWARE.

STOPPING FOR MINE-VENTILATING CROSSCUTS.

Original application filed February 15, 1919, Serial No. 277,177. Divided and this application filed March 24, 1920. Serial No. 368,454.

To all whom it may concern:

Be it known that I, JOSEPH F. JOY, a citizen of the United States of America, residing at Pittsburgh, in the county of Allegheny and State of Pennsylvania, have invented certain new and useful Improvements in Stoppings for Mine-Ventilating Crosscuts, of which the following is a specification.

This invention relates to certain new and useful improvements in stoppings for mine-ventilating cross cuts and has particular reference to an improved unitary stopping adapted for use in closing ventilating cross cuts or "break throughs" of coal mines.

15 The present application is a division of my copending application upon mining and apparatus therefor, Serial No. 277,177, filed February 15, 1919.

In places where coal mining is carried on, 20 there are laws designed to safeguard miners, and, among the most important, are those governing ventilation of the mines. A certain amount of fresh air must, in accordance with these laws, be delivered to each man per minute, and some of the air must be delivered past the working face of each mine room. In order to comply with the requirement of these laws, air passages or cross cuts are formed through the walls separating 25 rooms and entries, and, as the mining proceeds and new cross cuts are formed, it is necessary to close the previously made cross cuts in order to insure proper flow of the air forced into the mine. The closures for 30 cross cuts are usually termed "stoppings" and are each in the form of a wall or barrier built in a cross cut to prevent the air of the ventilating current from passing therethrough.

35 Prior to my invention, the building and maintenance of stoppings have been extremely costly items in the development of a coal mine or the production of coal.

It is an object of the present invention, 40 therefore, to provide an improved unitary stopping for cross cuts which may be bodily placed in or removed from a cross cut instead of being built in or removed in parts and destroyed, thus reducing to a minimum 45 the time and labor necessary therefor and to consequently greatly reduce the cost of the same.

A further object of the invention is to provide an improved stopping for cross cuts

which is of unitary form, simple in construction and efficient in preventing leakage of air and capable of being easily placed in position or removed for reuse. 55

With the above general objects in view and others that will become apparent as the 60 nature of the invention is better understood, the same consists in the novel combination, form and arrangement of parts hereinafter more fully described, shown in the accompanying drawing and claimed. 65

In the drawing wherein like reference characters designate corresponding parts throughout the several views,

Figure 1 is a diagrammatic plan view of a portion of a room-and-pillar mine formed 70 with cross cuts made in accordance with the present invention,

Figure 2 is a central sectional view of a stopping positioned in a cross cut and constructed in accordance with the present invention, 75

Figure 3 is a perspective view of the stopping shown in Fig. 2, and

Figure 4 is a view similar to Fig. 2 of a modified form of stopping. 80

Referring more in detail to the several views, 5 indicates the main entry of the mine into which air is forced by any suitable means, not shown. As indicated by arrows in Fig. 1, some of the air flows in this main 85 entry, and the rest is caused, by means of check cloths or the like, not shown, to pass into and through the rooms 6, the flow being from room to room through the open cross cuts 7. The open cross cuts 7 are those 90 nearest the working faces 8 of the mine rooms, it being understood that before said open cross cuts were formed, the stopping 9 was not used in the closed cross cut 10.

The back entry or return aircourse 11 is 95 driven parallel with the main entry 5, and in the development of the mine shown, a series of cross cuts 12 were successively formed through the wall separating the entries 5 and 11 and closed by a stopping 9 100 until the open cross cut 13 was made to allow the air to pass directly from the inner end of entry 5 to the inner end of entry 11 and then out as shown by arrows to a suitable point of discharge. 105

The foregoing description is directed to substantially what is now done in the development of mines, except that the cross

cuts as now formed are of no particular size or uniform shape in cross section and the stoppings of the cross cuts are specially built in to suit the particular size and shape of each cross cut. Also, the stoppings, as now formed, are of such nature that they are practically totally destroyed when removed for obtaining the pillar coal, while the cross cuts shown in the present drawing are circular and of a definite size so that a standard sized and unitary portable stopping, such as the one forming the subject matter of the present invention, may be used in any of the present cross cuts.

15 A great many types of stoppings are in use in the various coal mines of the United States, the types varying from efficient, but costly concrete stoppings to inefficient stoppings constructed of powder cans and coal dust. There are nine stoppings which are most prominently used, i. e., (1) rough lumber board, (2) tongue and groove board, (3) planed and painted board, (4) four inch brick, (5) eight inch brick, (6) concrete blocks, (7) concrete monolith, (8) slate or gob dry wall, and (9) slate or gob faced with cement. All of these stoppings are "built in" to suit each cross cut and some constantly require repairs while others are the cause of much loss of time when necessarily demolished and removed in the process of securing or mining the pillar coal.

30 By reason of the fact that I form the cross cuts of uniform or standard sizes and shape in cross section, I am enabled to practically make use of unitary, portable and reusable or bodily removable stoppings, sheet metal forms of which are shown in Figures 2 to 4. The machine for forming the circular standard sized and shaped cross cuts is shown, described and claimed in my above mentioned copending application.

35 In Figures 2 and 3, the stopping is in the form of a metallic disk 14 having a flanged annular band 15 riveted or otherwise concentrically fastened to one face thereof. The band 15 is of a slightly smaller diameter than the disk 14 so as to leave a projecting portion of the latter as 40 at 16 to form a backing against which the oakum or equivalent packing material 17 is packed, which material is placed between the band 15 and the surrounding wall of the cross cut 10 so as to prevent any material 45 leakage of air. A handle 18 may be provided to be grasped in the hand when initially positioning the stopping in or removing the same from the cross cut, and if it is desired to anchor the stopping, said 50 screws 19 may be threaded through the band 15 for engagement with the wall of the cross cut. It is to be understood that other anchoring means than the screws 19 may be used or the same may be entirely dispensed with.

55 In Fig. 4 the stopping also includes a disk 14 having an annular flanged band 15 riveted or otherwise concentrically fastened to one face thereof, but the band 15 in this instance is at least equal in diameter to the disk 14 and is reversely positioned when in use so as to engage the surrounding wall of the cross cut 10. In order to seal this form of stopping, wood fibre plaster or other suitable cement may be placed as at 20 where the stopping touches the wall of the cross cut similar to the manner in which putty is placed adjacent the edges of a glass pane when the latter is secured in a sash. This stopping also may have a handle 18.

60 From the foregoing description, it is thought that the many advantages as well as the construction and manner of use of the present invention will be readily appreciated and clearly understood by those skilled in the art.

65 Minor changes may be made in the forms, and combination and arrangement of parts without departing from the spirit and scope of the invention as claimed.

70 What I claim as new is:—

75 1. A stopping for fitting entirely into mine ventilating cross cuts comprising a disk of substantially the same diameter as the cross cut and having an annular flange adjacent to and spaced inwardly from the outer edge thereof, the flange being in the form of a laterally projecting band.

80 2. A stopping for entirely fitting into mine ventilating cross cuts comprising a disk of substantially the same diameter as the cross cut and having an annular flange adjacent to and spaced inwardly from the outer edge thereof, the flange being in the form of a laterally projecting band, and anchoring means for said stopping carrier 85 by said band.

85 3. A stopping for entirely fitting into mine ventilating cross cuts comprising a disk of substantially the same diameter as the cross cuts and having an annular flange adjacent to and spaced inwardly from the outer edge thereof, the flange being in the form of a laterally projecting band, and anchoring means carried by said stopping.

90 4. A stopping like that described in claim 3 wherein the disk is provided with a handle, and wherein the flange is spaced from the outer edge of the disk to receive packing material therearound between the outer face of the same and the inner face of the crosscut wall so that an air-tight joint may be had.

95 5. As an article of manufacture, a rigid sheet metal unitary stopping for removably fitting entirely into and closing ventilating cross cuts of mines.

100 In testimony whereof I affix my signature.
JOSEPH F. JOY.
